(57) CLAIM

The ornamental design for a shoe as shown and described.

DESCRIPTION

FIG. 1 is a front perspective view of a shoe showing my new design;

FIG. 2 is a side view thereof;

FIG. 3 is a rear perspective view thereof;

FIG. 4 is a front perspective view of a shoe showing a second embodiment of my new shoe design;

FIG. 5 is a side view thereof; and,

FIG. 6 is a rear perspective view thereof.

The uneven-length broken lines immediately adjacent to the front ends of the shaded areas define the bounds of the claimed design and form no part thereof. In FIGS. 1-3, the uneven-length broken lines within the shaded area represent stitching which forms no part of the claimed design. The seven circular uneven-length broken lines within the shaded area represent eyelets which form no part of the claimed design. The even-length broken line within the shaded area represents stitching which forms part of the claimed design. The uneven-length broken lines depicting the remainder of the shoe form no part of the claimed design.
